AUTOMOBILE DOOR HANDLE ASSEMBLY

Floyd A. Cooley, Detroit, Mich., assignor to
 Ternstedt Manufacturing Company, Detroit,
 Mich., a corporation of Michigan

Application March 13, 1942, Serial No. 434,571

7 Claims. (Cl. 292—347)

This invention relates to handle assemblies.

It is the object of the invention to provide a handle assembly which can be made of a screw machine product and suitable stamped metal parts or may be made of headed wire which forms the spindle and the core of the handle and sheet metal stampings.

Referring to the drawings:

Fig. 1 is a longitudinal section of the handle showing the handle spindle in elevation.

Fig. 2 is a plan view of the handle.

Fig. 3 is a cross-section of the handle showing the handle spindle and the core of the handle in elevation.

Fig. 4 is a longitudinal section of a modified form of handle but involving the same general principle.

Fig. 5 is a cross-section of this handle taken along the axis of the handle spindle and showing the handle spindle and core in elevation.

Fig. 6 is a section taken on the line 6—6 of Fig. 4.

Fig. 7 is an end view of the outer handle shell.

Fig. 8 is a longitudinal section of another modified form.

Fig. 9 is a similar section of still another form.

Referring to Fig. 1, 1 designates the outer door panel, 2 the overlap flange and 3 the jamb face of the door. 4 shows the belt molding.

The handle spindle and handle stem are formed of a piece of wire stock or a screw machine product that is properly headed. 5 designates the handle spindle which has an enlarged bearing portion 6 and an annular flange 7. 8 designates a handle stem which is butt welded at 9 to the end of the handle spindle. A cap piece 10 is provided with a boss 11 and this boss may be projection-welded to the annular flange 7 of the handle spindle. The handle stem 8 may be bent to shape either before or after it is welded to the end of the handle spindle.

The outer shell 12 is a stamping that is folded to the shape shown in Figs. 1, 2 and 3. This is a substantially closed channel, the edges 13 and 14 coming close to meeting on the under side of the handle. After the cap piece 10 has been projection-welded to the flange 7 and the handle stem has been welded to the spindle and bent to the proper curvature, the outer shell, which has been folded to the shape shown in Figs. 1, 2 and 3, is telescoped over the curved handle stem and the enlarged end of the shell telescoped over the flange 15 of the cap piece. Thereupon, the edge 16 and the tabs 17 and 18 are folded over the

edge of the flange 15 of the cap piece to complete the assembly.

The enlarged bearing portion 6 is fitted in a bushing 19. This bushing 19 is supported in a rubber sleeve 20. The rubber sleeve 20 is first passed through the belt molding and an opening in the inner panel 1. Then the bushing 19 is passed through the rubber sleeve and the inner end expanded as at 21 to hold the bushing assembly in place.

In the modified form shown in Figs. 4—7, the handle stem and the handle spindle are one continuous integral piece made from headed wire stock or turned on a screw machine. The handle shell is made, however, the same way and has the same tabs 17 and 18 which are crimped over the edge of the flange of the cap piece to assemble the parts together when the handle shell is telescoped over the handle stem. The cap piece is spot welded as at 22 to the annular flange 7. The handle stem, where it merges into the handle spindle, is notched out as at 23 to provide a weakened portion so that in case the handle is forced by a tool, such as a pipe, the handle will break rather than the lock parts. This is to prevent some unauthorized person forcing his way into the car when it is parked.

In the type of handle shown in Figs. 1 to 3 inclusive an annular groove 24 is provided at one side of the flange 7 to provide a weakened portion where the handle spindle will break when forced. If the handle has been forced and broken, one may get into the car by taking a pair of pliers and grasping the head 6 and turning the spindle.

In the modified form of the invention shown in Fig. 8 the same general form of the invention is shown, but here the enlarged bearing portion 6 is omitted and the bearing is formed by a punched-out sleeve portion 25 punched out of the cap piece. A weakened portion 24a is formed by a groove in the handle spindle 5a.

In the form of the invention shown in Fig. 9 the cap piece has a turned-in flange 15b instead of the turned-out flange 15 shown in the other figures. The bearing is formed by a punched-out sleeve portion 25b the same as in Fig. 8.

What I claim is:

1. A handle assembly, particularly for outside handles for automobile doors, comprising a rod-like handle spindle and stem with an enlarged bearing portion adapted to fit into a bushing or escutcheon in the door and having also an enlarged annular flange, the said handle stem being arranged in angular relation with respect to

the handle spindle, a flanged cap piece welded to said flange and a stamped and a folded metal shell of a substantially closed channel cross-section having an enlarged open inner end, said shell being telescoped over the handle stem and the flange of the cap piece and the inner end portion of the shell secured to the flange of the cap piece.

2. A handle assembly, particularly for outside handles for automobile doors, comprising a rod-like handle spindle and stem with an enlarged bearing portion adapted to fit into a bushing or escutcheon in the door and having also an enlarged annular flange, the said handle stem being arranged in angular relation with respect to the handle spindle, a cap piece provided with a turned-over flange and welded to the said flange and a stamped and folded metal shell of a substantially closed channel cross-section having an enlarged open inner end, said shell being telescoped over the handle stem and the inner end portion of the shell provided with projecting tabs which are crimped over the edge of the turned-over flange of the cap piece.

3. A handle assembly, particularly for outside handles for automobile doors, comprising a rod-like handle spindle and stem with an enlarged bearing portion adapted to fit into a bushing or escutcheon in the door and having also an enlarged annular flange, the said handle stem being arranged in angular relation with respect to the handle spindle, a flanged cap piece provided with a boss projection-welded to said flange and a stamped and folded metal shell of a substantially closed channel cross-section having an enlarged open inner end, said shell being telescoped over the handle stem and the inner end portion of the shell welded to the flange of the cap piece.

4. A handle assembly, particularly for outside handles for automobile doors, comprising a rod-like handle spindle and stem butt welded together with an enlarged bearing portion adapted to fit into a bushing or escutcheon in the door and having also an enlarged annular flange, the said handle stem being arranged in angular relation with respect to the handle spindle, a cap piece welded to said flange and a stamped and

folded metal shell of a substantially closed channel cross-section having an enlarged open inner end, said shell being telescoped over the handle stem and the inner end portion of the shell secured to the cap piece.

5. A handle assembly, particularly for outside handles for automobile doors, comprising a rod-like handle spindle and stem with an intervening weakened or notched portion and with an enlarged bearing portion adapted to fit into a bushing or escutcheon in the door and having also an enlarged annular flange, the said handle stem being arranged in angular relation with respect to the handle spindle, a cap piece welded to said flange and a stamped and folded metal shell of a substantially closed channel cross-section having an enlarged open inner end, said shell being telescoped over the handle stem and the inner end portion of the shell telescoped over and secured to the cap piece.

10 6. A handle assembly, particularly for outside handles for automobile doors, comprising a rod-like handle spindle and a stem adapted to pass through a bushing or escutcheon in the door and having an annular flange, said handle stem being arranged in angular relation with respect to the handle spindle, a cap piece welded to said flange and a stamped and folded metal shell of substantially closed channel cross-section having an enlarged open end, said shell being telescoped over the handle stem and the inner end portion of the shell secured to the cap piece.

15 7. A handle assembly, particularly for outside handles for automobile doors, comprising a rod-like handle spindle and stem arranged to pass through a bushing or escutcheon in the door and having an annular flange, the said handle stem being arranged in angular relation with respect to the handle spindle, a cap piece welded to said flange and provided with a punched-out sleeve fitting around the handle spindle and arranged to form a bearing to fit in the bushing or escutcheon and a folded metal shell of substantially closed channel cross-section having an enlarged open inner end, said shell being telescoped over the handle stem and the inner end portion of the shell secured to the cap piece.
